Patented Aug. 26, 1975

236,483

CALCULATING MACHINE

Myron Beitler, West Orange, and Douglas H. Graham,
Boonton, N.J., assignors to Litton Business Systems,
Inc.

Filed Sept. 13, 1973, Ser. No. 397,155

Term of patent 3½ years

Int. Cl. D18—01

U.S. Cl. D26—5 C

FIG. 1

FIG. 2

FIG. 6

FIG. 3

FIG. 5

FIG. 4

FIG. 1 is a perspective view of a calculating machine showing our new design;

FIG. 2 is a top plan view thereof;

FIG. 3 is a bottom plan view thereof;

FIG. 4 is a right side elevational view thereof;

FIG. 5 is a rear elevational view thereof; and

FIG. 6 is a front elevational view thereof.

The left side elevational view of the machine is substantially identical with and a mirror image of the right side elevation thereof shown in FIG. 4.

We claim:

The ornamental design for a calculating machine, as shown and described.
